HEADBOARD FOR BEDS

Louis Elliott Frey, Los Angeles, Calif.

Application May 23, 1955, Serial No. 36,159

Term of patent 14 years

(Cl. D5—4)

FIG. 1.

FIG. 2.

Fig. 1 is a front perspective view of a headboard for beds, with the bolster shown in lowered position, embodying my new design.

Fig. 2 is a front perspective view thereof, with the bolster shown in raised position.

The dominant features of my design are shown in solid lines. The broken lines depicting the bed are for illustrative purposes only.

I claim:

The ornamental design for a headboard for beds, substantially as shown and described.
